VULCAN FOUNDRY LIMITED, OF NEWTON-LE-WILLOWS, ENGLAND.

RIVETING-MACHINE.

PRINTED

1,165,851.

Specification of Letters Patent. Patented Dec. 28, 1915.

Application filed June 27, 1914. Serial No. 847,632.

To all whom it may concern:

Be it known that I, WILLIAM COLLINGWOOD, a subject of the King of Great Britain, residing at Locomotive Works, New-ton-le-Willows, in the county of Lancaster, England, have invented certain new and useful Improvements in or Relating to Riveting-Machines, of which the following is a specification.

10 This invention relates to riveting machines, especially of the pneumatic type, and provides an improved form of apparatus enabling the riveting operation to be effected by riveting tools applied to both ends 15 of the rivet or stay independently or simultaneously, so that the ordinary holder up is dispensed with.

According to this invention two riveters or hammers are so mounted on opposed supports as to enable one tool to be applied to one end of the rivet or stay while the other tool is applied to the other end, either tool acting as holder up to the second tool. The tools may synchronize in their action or 25 may work alternately or independently, so that both heads of the rivets or stays may be formed simultaneously or one after the other as found desirable. The combined riveters maintain a continuous though variable holding pressure on each head of the rivet or stay while blows are independently delivered to one or both ends.

A convenient method of support is to mount the two riveters adjustably in the 35 ends or heads of the arms of a horse shoe or yoke frame which can be suspended by means of a ring or like device carried by a screw rod extending across the upper part or middle of the horse shoe and displaceable 40 on the said rod. The force of the blows and the holding up pressure may be adjusted from either side of the machine by varying the distance between the two riveters, and this distance can be regulated during the 45 formation of the rivet or stay heads.

The riveters (or one of them) may be mounted in pivoted heads so that they may be directed at any desired angle to each other. The pivots may also be adjustable 50 eccentrically or otherwise in the frame to allow the riveters to be raised or lowered relatively to each other.

In order that the said invention may be clearly understood and readily carried into

effect I will describe the same more fully with reference to the accompanying drawings, in which:

Figures 1 and 2 are elevations of a riveting machine embodying my invention, the riveters or hammers being mounted in pivoted or swiveling heads. Fig. 1^a is a detail view of one of the heads, and Figs. 3 and 4 are detail views showing respectively a fixed head and a piston and fluid pressure device for holding up and releasing the rivet.

A is the frame of horse-shoe or yoke form with riveting heads B at the ends of the two arms.

C is a screw rod at the upper part of the frame, receiving the ring bar c and turned 70 in bearings a by means of the pulley c' and chains c².

D, D are the riveters or hammers, of the usual construction and provided with the trigger d by which the hammer air pressure is controlled.

Referring to Fig. 1 the heads B are pivoted to the frame arms at b, the frame being shown as constructed of two plates connected together by short stays a'. The heads D 80 lie between the lower ends of the two plates. The head is adjusted pivotally by a worm E mounted in bearings e in the frame and provided with a small hand wheel e' by which it is turned, the worm engaging worm 85 teeth at the end of the arm or extension b* of the head B. A spring stud e² may be used to lock the wheel in adjusted position. The chain lines x—x indicate the range of angular adjustment allowed to the heads and 90 therefore to the riveters, so that the latter may be set to form heads at right angles to the axis of the stay or one or both of the stay heads may be formed at an oblique angle to the stay axis. An example of the 95 work to which the riveting machine may be applied is shown between the riveters, comprising two plates F connected by stays f. The work shown in chain lines has the plates 100 slightly diverging and in this case the stay heads would have to be formed obliquely with relation to the axes of the stays.

The riveters or hammers may be mounted in sleeves G screwed into the tapped eyes or nuts b' of the heads B and adjusted by 105 the handle g, which is adjacent to the trigger d so that both can be held in one hand. The sleeve is adjusted in the head so as to

move the riveter nearer to or farther from the work and thus to increase or decrease the force of the holding up pressure or the blows, which are also controlled by the trigger d in the usual manner. The riveter is held in the sleeve G by the thrust clips g' securely fixed to the sleeves. To take up wear in the screw the eye b' is split and a set screw b^2 (Fig. 2) is provided to tighten 10 up the eye when necessary, so that there may be no looseness in the mounting of the sleeve G . In some cases the separate sleeve G may be dispensed with and the riveter screwed directly into the nut b' . The adjustment in this case is similar to that already described.

The head B shown at the right hand side of Fig. 1 and in Fig. 1^a has a further adjustment which enables the pivot axis to be 20 displaced so that one riveter or hammer D may move up or down relatively to the other. For this purpose the head B is mounted on an eccentric pin b^3 which can be turned in the end of the frame by means 25 of an adjusting handle b^4 and locked in adjusted position by the locking handle b^5 or other convenient means. The worm teeth b^6 engaged by the worm E are arranged on the face of the arm b^* and are 30 mounted on the pivot pin b^7 to allow the angle of the teeth to adjust themselves to the worm as the arm b^* turns. The teeth are vertically cut and slide over the worm without disengaging, during the adjustment 35 of the eccentric b^3 .

Apart from the angular adjustment of the riveter heads the frame A as a whole may be suspended at an angle by displacing the ring c along the screw rod C on either 40 side of the central axis of the frame. This is effected by turning the pulleys c' , so that the whole apparatus is under complete control during the progress of the work. To enable operators who are not in sight of 45 each other, owing to the intervening work, to signal any alteration in position required, the signaling arms H at the sides of the frame are connected by the rods h and bell crank levers h' so as to move together.

50 In the modification shown in Fig. 3 the head B' is fixed in the ends of the frame A so that no angular adjustment of the riveter is permitted. Otherwise the construction may be the same as that already described. 55 One arm of the frame A may be provided with a fixed head B' and the other with an adjustable head B if found convenient for the work.

In the modification illustrated in Fig. 4 60 a pivoted head B^2 is shown, but instead of mounting the riveter in a screwed sleeve the head B^2 is made in the form of a fluid pressure cylinder and the riveter is provided with a piston d' which slides in this 65 cylinder. The riveter is held up to and re-

leased from its work by the air pressure on the back of the piston and the handle b^8 , which corresponds to the sleeve adjusting handle g of Fig. 1, regulates the pressure of the air and thus the holding up force of the 70 tool.

The machine may be made with fluid pressure holding up devices for both riveters or for one only as found desirable.

What I claim and desire to secure by 75 Letters Patent of the United States is:—

1. In a riveting machine, two opposed riveter supports, two pneumatic hammers mounted in said supports so as to oppose each other, and means for adjusting one of 80 said hammers axially in its support.

2. In a riveting machine, a suspended frame having two oppositely situated riveter supports, two pneumatic hammers mounted in the said supports so as to oppose each 85 other, and means for adjusting one of the said hammers axially in its support.

3. In a riveting machine, a frame having depending arms, riveter supports in the ends of the said arms, a screwed suspension rod 90 in bearings at the top of the frame, means for turning the said rod, a suspension device adjustably mounted on the rod, and two riveters mounted in the said supports so as to oppose each other.

4. In a riveting machine, two opposed riveter supports, and two riveters mounted in the said supports so as to oppose each other and an adjustable nut and screw connection between the riveters and the supports. 95

5. In a riveting machine, two opposed riveter supports, two riveters, screw threaded sleeves screwing adjustably in the riveter supports and thrust clips securing the said 105 riveters in the sleeves.

6. In a riveting machine, a frame having two depending arms with riveter supports, two opposed riveters mounted in the said supports and a signaling device extending 110 from one side of the frame to the other.

7. In a riveting machine, a frame with two opposed riveter supports of which one is pivoted in the frame, an arm on the said pivoted support and a worm engaging said 115 arm for varying the angular position of the arm and support.

8. In a riveting machine, a frame with two opposed riveter supports each of which is pivoted in the frame, arms on the said supports and an adjusting worm between each arm and its support. 120

9. In a riveting machine, a frame with two opposed riveter supports of which one is pivoted in the frame, means for angularly 125 adjusting the said pivoted support and means for displacing the pivot axis in the frame.

10. In a riveting machine, a frame with two opposed riveter supports of which one is 130

pivoted in the frame, means for angularly adjusting the said pivoted support and an eccentric for adjusting the pivot axis.

11. In a riveting machine, a frame with two opposed riveter supports, an eccentrically mounted pivot on which one of the said supports is carried, means for angularly adjusting the said pivoted support, means for angularly adjusting the eccentric pivot and means for securing the said pivot in adjusted position.

12. In a riveting machine, a frame with two opposed riveter supports, an eccentric

cally mounted pivot on which one of the said supports is carried, means for angularly adjusting the said pivoted support, an adjusting arm on one end of the said eccentric pivot whereby the pivot is angularly adjusted and a locking arm on the other end of the pivot.

In testimony whereof I affix my signature in presence of two witnesses.

W. COLLINGWOOD.
